(57) **CLAIM**

The ornamental design for an electronic module for a dog collar, as shown and described.

DESCRIPTION

FIG. 1 is a front perspective view of an electronic module for a dog collar showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The structural features depicted by broken lines in FIG. 3 have been shown for the purpose of illustrating portions of the electronic module for a dog collar that form no part of the claimed design.
